Elmer J. Renner, Aurora, Ill., assignor to Stephens-Adamson Mfg. Co., a corporation of Illinois

Application October 10, 1955, Serial No. 539,503

15 Claims. (Cl. 214—89)

This invention relates to cargo handling apparatus, and more particularly to such a cargo elevator that will receive a moving pallet loaded with cargo and raise it automatically to a predetermined height.

A cargo elevator of this type is especially useful for receiving a load of cargo from a cargo accumulation station and lifting it to within reach of an airplane cargo hold so that it may be loaded into the airplane. The cargo elevator of this invention may be used, for instance, to lift cargo pallets off an endless conveyor belt and raise them into position for transfer of the cargo to a plane which has been brought into position next to the conveyor belt.

To be adapted for such use, a cargo elevator should operate as nearly fully automatically as possible, in order to free the attention of the baggage men so that they may carry out the irreducible minimum of tasks that must in any event be done manually in any loading or unloading operation. If more than one cargo hold is to be loaded, the cargo elevator for each hold must be so constructed that its operation will not interfere with but, on the contrary, can be coordinated with the operation of the elevators at the other cargo holds. The cargo elevator must be reliable in operation and sturdy of construction, yet not so large as to interfere with either the plane itself or the other baggage handling apparatus such as the endless conveyor belt.

The apparatus of this invention achieves all these aims. The apparatus is comprised of a hoist having switch means for selectively causing the hoist to be raised or lowered, a mobile cargo pallet which carries means to trip said switch automatically when the pallet comes into position to be lifted by the hoist, and means to propel the pallet to the hoist, the propelling means being adapted to be rendered inoperative after the cargo pallet has been raised a predetermined distance.

The invention will be described by reference to the embodiment shown in the accompanying drawings. In the drawings:

Figure 1 is a diagrammatic perspective view showing one embodiment of the cargo elevator of this invention as it may be used with an airplane to be loaded with cargo;

Figure 27 is a schematic diagram of the electrical circuits for actuating the hydraulic systems of the cargo hoists of the system shown in Figure 1, including an 45 interlock circuit that connects the electrical circuits of the hoists in that system.

General description of cargo elevator in use

The cargo elevator of this invention is shown diagrammatically in Figure 1 as used for handling cargo to be loaded and unloaded from an airplane. Cargo elevators 30, 31 and 32 are shown in position near cargo holds 33, 34 and 35 of airplane 36. The cargo elevator of this invention may also be employed in any other system in which cargo moves to and from the elevator.

In the embodiment shown, cargo elevators 30, 31 and 32 are used with endless conveyor 37. Conveyor 37 leads from a cargo accumulation station (not shown) located at the left and rear of plane 36, to a point just behind the plane, and from there along the right side of the plane to a short distance beyond the nose. Conveyor 37 includes endless conveyor belt 38 leading from the cargo accumulation station, curved endless conveyor belt 39 which changes the direction of conveyor 37, and endless conveyor belt 40 which runs along the side of plane 36. Conveyor 37 also includes tracks 41 on either side of endless conveyor belts 38, 39 and 40.

Items of passenger luggage, freight or air mail may be brought from the cargo accumulation station for loading on plane 36 either upon conveyor belts 38, 39 and 40 or upon mobile cargo pallets 45, 46 and 47, which are parts of cargo elevators 30, 31 and 32, respectively. Cargo

pallets 45, 46 and 47, while moving from the cargo accumulation station to plane 36, ride upon tracks 41 of conveyor 37.

As will be explained below, cargo pallets 45, 46 and 47 can be sent out to plane 36 on conveyor 37 either loaded with cargo to be delivered to the plane, or in an empty condition for unloading cargo from the plane. When a cargo pallet arrives at its associated cargo hold, it interacts with the rest of the cargo elevator at that location to raise the cargo carried by the pallet toward the hold into which the cargo is to be transferred. By means to be explained below, the operation of any particular one of cargo elevators 30, 31 and 32 to raise the cargo carried by the pallet which is a part of that particular elevator may be made automatic. Cargo elevator 30 is arranged to be actuated only by the arrival of cargo pallet 45, cargo elevator 31 by the arrival of pallet 46 and elevator 32 by the arrival of pallet 47.

Figures 2 and 3 show in plan view the path along which conveyor 37 leads from the cargo accumulation station to plane 36 and along the side of the plane to the forward end of the plane. Conveyor belt 38 approaches plane 36 at the rear of the plane along a path lying at right angles to the longitudinal axis of the plane. Conveyor belt 39 makes a curved right angle turn in the vicinity of the rear of plane 36. Conveyor belt 40 then continues along the side of the plane. Tracks 41 flank the conveyor belts along the entire path. In Figures 2 and 3 conveyor belts 38 and 40 and the associated tracks 41 are broken away to show that the length of conveyor 37 may be adapted to any size airplane and any airport layout.

Hoist 48 of cargo elevator 30 is located, as shown in Figure 2, near the most rearward cargo hold 33 of plane 36. Hoists 49 and 50 of cargo elevators 31 and 32, respectively, are located at forward cargo holds 34 and 35. Figure 4 shows in side elevation the location of hoists 49 and 50. It also indicates (in broken line) how cargo hoist 50 may be raised from its down or collapsed position (shown in solid line) into its most elevated position.

Figure 5 shows a sealing lip 51 which closes the gap between the ends of conveyor belts 38 and 39 or between belts 39 and 40. For clarity, sealing lip 51 is omitted from Figure 2.

Hoist

Figure 6 gives a side elevation of hoist 49 when in its collapsed or down position. The hoist is shown in broken lines in an intermediate position to which it may be raised by actuation of the elevating mechanism of the hoist, and also in broken lines in its uppermost position after it has been fully elevated.

Hoist 49 includes two elevating members 51 and 52 spaced on either side of conveyor 37. The elevating member of hoist 49 which is seen in Figure 6 is member 52. Cargo pallet 46, which is adapted to actuate hoist switch 53 as it depresses cam bar 54 upon passing over elevating member 52, approaches from the left in the drawing shown in Figure 6.

When cam bar 54 is depressed, this operates cam lever 55 which in turn energizes hoist switch 53. When panel 54 is depressed, it pushes down the upper end 56 of cam 55. As the cam is pivoted by rotatable attachment to elevating member 52, the lower end of the cam is caused to rise and push against wheel 57 of limit switch 53.

Limit switch 53 is connected in the electrical circuit of the motor that drives the hydraulic pump for cargo hoist 49. The pump is connected to hydraulic ram 60 on one side of cargo hoist 49, and to ram 60a (shown in Figures 7 and 9) on the opposite side of the hoist. Ram 60 is rotatably attached at its bottom end to base member 61 of cargo hoist 49. Piston 62 extends from the upper end of hydraulic ram 60, and is rotatably attached at its upper end to upright member 63 of hoist 49, located at the rear end of the hoist. In the same

way, the bottom end of ram 60a and top end of piston 62a are rotatably attached to base member 61a and upright member 63a, respectively, on the other side of the hoist.

Upright 63 at one end of hoist 49 and upright 64 at the other are pivoted at their lower ends about axles 65 and 66, respectively. These axles are journaled at one end in base member 61, seen in Figure 6. Axles 65 and 66 extend across to the opposite side of hoist 49, where they are journaled in base member 61a and carry pivoted members 63a and 64a, all corresponding to the similarly numbered members which are seen in Figure 6.

Platform 67 also extends from one side of cargo hoist 49 to the other, serving both to carry the major part of the hydraulic system of the hoist (as explained below) and also to help provide rigidity between base members 61 and 61a on opposite side of the hoist.

Elevating member 52 is supported by uprights 63 and 64, to which it is rotatably attached at either end. Elevating member 51, on the opposite side of cargo hoist 49, is similarly supported by uprights 63a and 64a. Cross bars 68 and 68a, respectively, reinforce uprights 63 and 64 on one side of the hoist and uprights 63a and 64a on the other. The cross bars are rotatably attached at each end to the uprights they enforce.

The framework of cargo hoist 49 that results from this arrangement of members has the appearance when in its most elevated position of a box frame riding upon two wheel-bearing axles, the frame having no cross pieces at the top, and a wide platform cross member at one end of the bottom. The box frame is collapsible in the direction of the end of the hoist at which hydraulic rams 60 and 60a are rotatably attached to base members 61 and 61a.

At all stages of collapse of this box frame and later return of the frame to the upright position, the frame maintains (by means described below) its parallelepiped shape. The result is that elevating members 51 and 52 sweep through the same arc on both sides of cargo hoist 49, maintaining at all times their parallel relation and their equal heights above the ground.

When hoist switch 53 is closed, the hydraulic pump of hydraulic rams 60 and 60a is caused to operate. This forces pistons 62 and 62a to be moved out of the cylinder of rams 60 and 60a. As seen from the intermediate broken line position of cargo hoist 49 shown in Figure 6, pushing piston 62 out of the cylinder of ram 60 forces upright 63 to rotate at its bottom end about rear axle 65. As upright 63 rises from the collapsed position, cross bar 68 and elevating member 52 pull up through a similar path upright member 64 at the other end of elevating member 52.

As piston 62 is pushed farther out of the cylinder of ram 60 by continued operation of the hydraulic pump of the system, uprights 63 and 64 continue to approach the vertical position until elevating member 52 has reached its highest position, which is shown in broken line in Figure 6. At the same time, elevating member 51 is moved up into the same relative position on the other side of the hoist.

As stated above, the first part of the rise of cargo hoist 49 is accomplished automatically upon depression of cam bar 53. The second part of the rise of the hoist is produced (as will be described below) by manual operation of a switch. When the hoist has reached its extreme elevated position, the manual switches are no longer actuated and no additional hydraulic pressure is applied. Since the hydraulic system is fluid tight, the position taken by the hoist is a stable one.

In fact, hoist 49 will remain in any elevated position at which it comes to rest when actuation of the manual switch ceases. The positions to which hoists 48, 49 and 50 are raised depends upon the height of cargo holds 33, 34 and 35 which are being serviced by the hoists.

Cargo hoist 49 is shown in Figure 6 as being carried

on wheels adapted to ride upon plate 69 and corresponding plate 69a on the other side of the hoist. Within predetermined limits, cargo hoist 49 may be moved forward or backward, as desired. This provides additional flexibility in the use of the apparatus of this invention, for it permits forward and rearward adjustment to be made in the position of cargo hoist 49 depending upon the location, for example, of cargo hold 34 in the plane which is being loaded or unloaded.

As best seen from Figure 9, rear wheel 70 is supplemented in the embodiment shown by other wheels 70a, 70b and 70c, all carried upon axle 65. Similarly, wheel 71 seen in Figure 6 is supplemented by wheels 71a, 71b and 71c, all carried by axle 66.

The center of gravity of cargo hoist 49 shifts markedly when upright members 63 and 64 collapse from the vertical position to a near horizontal position and return to the vertical. This shift is made even more marked by addition of the weight of pallet 46 and the cargo it carries when these are raised or lowered upon elevating members 51 and 52. The pallet and its cargo tend to tip hoist 49 forward over front axle 66, raising wheels 70 off the ground at the rear end of the hoist.

One factor opposing the tendency of hoist 49 to tip forward when loaded is the placement of the motor, pump and hydraulic mechanism which operate the hoist. These are for the most part supported upon platform 67 at the rear end of hoist 49. The weight of this equipment helps to counterbalance the shift in center of gravity as the pallet and load are lowered, or as they are first caused to be raised, by elevating members 51 and 52.

Another means of opposing this shift in the center of gravity of the loaded cargo hoist is to place a counterweight of concrete or similar heavy material upon platform 67 at the rear end of hoist 49.

Still another means of counteracting the shift in center of gravity of hoist 49 is to provide a hold-down device which will operate to keep wheels 70, 70a, 70b and 70c from being lifted very far, if at all, off plates 69 and 69a. Such a hold-down device is seen in Figure 9, where bracket 75 is connected to plate 69 at its bottom end and overhangs wheel 70 at the top. Bracket 75 extends along conveyor 37 for the same distance it is desired to move hoist 49 to accommodate different locations of cargo holds of airplanes with which the hoist is used. A similar hold-down device 75a is provided on the opposite side of cargo hoist 49 to help hold down wheel 70c. (Hold-down device 75 has been omitted for clarity from Figures 6 and 14A.)

The cargo hoist of this invention may be designed to ride upon rails 76 as shown in Figures 10 and 11 rather than upon plate 69. In this embodiment, there is a pair of flanged wheels 77 on each side of cargo hoist 49. The wheel shown in Figures 10 and 11 is at the left rear end of hoist 49. It occupies, in other words, the same relative position with respect to the cargo hoist as the wheels 70b and 70c shown in Figure 16.

In this embodiment, base member 61a has welded to it angles 78 and 79, which together form a hold-down device which will counteract the upsetting tendency described above. Angles 78 and 79 embrace flange 80 at the top of rail 76 upon which wheels 77 ride. Grasping the bottom part of flange 80 on both sides, angles 78 and 79 keep base member 61a and therefore axle 65 and wheel 77 all in their operative positions, with the wheel riding upon track 76.

Figures 9, 12A and B, 14A and B, and 15 show in more detail how cargo hoist 49 raises cargo pallet 46 into its elevated position. From these figures can be seen the movement by which hydraulic rams 60 and 60a force pistons 62 and 62a into an extended position, thus elevating upright members 63 and 63a until the latter are in a vertical position. As seen from Figures 14A and 14B, in this position cross bar 68 and elevating member 52 are horizontal. Elevating members 51 and 52 are both

raised, as seen in Figures 12A and 12B, to their extreme upper position, and they have carried with them cargo pallet 46.

Upright 63 is comprised of two channel members 63' and 63'' which face each other and are connected by a wide plate 81 at their bottom ends and a second wide plate 82 at their top ends. Members 63' and 63'' each have a hole at the bottom end through which axle 65 passes. Thus the upright member forms a yoke through which the axle for wheels 70, 70a, 70b and 70c passes.

The upper end of hydraulic piston 62 is rotatably attached to upright member 63 by means of rod 83 which is journaled in housings 84' and 84'' attached to uprights 63' and 63'', respectively. Horizontal members 68' and 68'' are rotatably attached to uprights 63' and 63'', respectively, at the rear end of hoist 49 and to the corresponding upright members at the front end of the hoist.

Elevating member 52 is connected at the top of upright 63 through a construction somewhat similar to the connection of the same upright to axle 65 at the bottom of the hoist. Elevating member 52 is a wide channel member which rides with its open portion facing downward, so that the sides of the channel overlap the top of upright 63. The top of upright 63 is formed in a yoke somewhat like that at the bottom of the upright. Connecting rod 90 provides a means of rotatably attaching the yoke so formed to the side walls of the channel comprising elevating member 52.

The same type of construction is used for the other three upright members and elevating member 51. The upright members all have a relatively large transverse dimension in comparison to their height. This gives them a degree of stability in a transverse direction which is especially important in a cargo hoist which is used to elevate loads having the weight of cargo pallet 46 and the cargo it carries.

When cargo hoist 49 is in its down or collapsed position with upright members 51 and 52 at a height just flush with tracks 41 and conveyor belt 40, the frame of the hoist has not yet been swung down to the very lowest position it could possibly assume. Hydraulic rams 60 and 60a tend to keep uprights 63 and 63a at the desired angle to the horizontal, after additional hydraulic pressure is no longer applied to move hoist 49 down to its bottom position. Stop 91, shown in Figure 6, provides an additional, mechanical means of keeping upright 63 at the proper angle when hoist 49 is in its down position. Stop 91a, on the other side of the hoist, does the same for upright 63a. The stops, located about midway between the ends of hoist 49, are carried by base members 61 and 61a, respectively.

The construction of cargo hoist 49 is shown in plan view in Figure 7. In that figure, cargo pallet 46 approaches the hoist from the right hand side of the drawing. Conveyor belt 40, flanked by tracks 41, passes between elevating members 51 and 52. Elevating member 52 is supported on upright members 63 and 64, while elevating member 51 is supported on upright members 63a and 64a.

The hoist is shown in Figure 7 in its down or collapsed position. In this position, hydraulic pistons 62 and 62a are withdrawn into the cylinders of hydraulic rams 60 and 60a. When the pistons are extended from the cylinders by application of hydraulic pressure at the bottom end of the cylinders, elevating members 51 and 52 are caused to swing upward in an arc from the position they occupy in Figure 7, and as they do so they also move to the right in that drawing.

Hoist switch

As shown in Figures 9 and 12B, elevating members 51 and 52 carry guide chutes 92 and 93, respectively. These have been omitted for clarity from Figure 14B.

The guide chutes on hoist 49 are located in the middle 75 of the elevating members. Guide chute 92 operates to

guide cam roller 94 directly to cam bar 54 as cargo pallet 46 rolls upon elevating members 51 and 52 while cargo hoist 49 is in its down or collapsed position. Guide chute 93 keeps guide roller 95 in the proper transverse position so that cam roller 94 will maintain its correct transverse position for tripping cam bar 54. Cam roller 94 and guide roller 95 are both at the front end of cargo pallet 46. Similar rollers are located in the same positions at the rear of the cargo pallet, but for clarity have been omitted from Figures 9 and 12B.

From Figure 9 it is seen that cam rollers 100 and 101 (shown in phantom) may be carried at the front end of other cargo pallets in positions from which they will selectively actuate other cam bars 102 and 103 located on cargo hoists 50 and 48, respectively. Similarly, guide rollers 104 and 105 may be located in corresponding positions on the other side of cargo pallets 47 and 45, respectively.

In the embodiment shown in Figures 6, 8, 14B and 15, the hoist switch mechanism is for clarity shown on elevating member 52 on the right side of hoist 47 (as the hoist is approached by cargo pallet 46), rather than on the left side as in Figures 7, 9, 12B and 16. The hoist switch is shown on the left hand side of cargo hoist 50 in Figures 18 and 19, and on the left hand side of cargo hoist 48 in Figure 21. The hoist switch may in fact be located on either side of the cargo hoist, as desired. One advantage of locating the switch on the right hand elevating member (the elevating member which is farther from the plane being loaded or unloaded) is that in this position there is less chance of accidental actuation of the hoist switch by baggage handling personnel, one of whom might inadvertently step upon the cam bar which controls the switch.

Figure 15 shows the position occupied by cam bar 54 as cam roller 94 approaches it when cargo pallet 49 is moved along conveyor 37 by conveyor belt 40. In this position, elevating member 52 is substantially flush horizontally with the top surface of conveyor belt 40. As seen, upright 64 lies in a collapsed position with horizontal member 68 and elevating member 52 depressed accordingly. Figure 8 shows the position occupied by cam bar 54 after it has been depressed.

Cam lever 55 rotates about fulcrum 110 which is attached to elevating member 52. The bottom end of cam lever 55 presses against switch wheel 57, which is adapted to actuate hoist switch 53. The upper end of cam lever 55 is rotatably attached to cam bar 54 by means of hinge 56.

The other end of cam bar 54 carries adjusting arm 111, which is rotatably attached to the cam bar at its upper end and to elevating member 52 through fulcrum 112 at its lower end. The lower end of adjusting arm 111 extends beyond fulcrum 112 to provide a seating 113 for adjusting bolt 114. Bolt 114 is screwed through arm end 113, with the threaded end of the bolt pressing against adjusting stop 115, which is attached to elevating member 52. As adjusting bolt 114 is screwed into or out of portion 113 of arm 111, this moves portion 113 away from or permits it to move toward stop 115, respectively. The upper end of arm 111 is thus moved down as the arm rotates about fulcrum 112 or is permitted to move higher when cam bar 54 is urged upward by means to be described. By employing adjustment of bolt 114 to lower or raise, as desired, the end of cam bar 54 to which adjusting arm 111 is attached, the distance cam bar 54 must be depressed before switch 53 is actuated can be varied, and thus the rapidity of response of the hoist switch to arrival of cargo pallet 46 can be controlled.

Cam bar 54 is supported in its uppermost position by spring 116, the bottom end of which is secured to elevating member 52. When cam bar 54 is in this position, switch wheel 57 of hoist switch 53 is in contact with the bottom end of cam lever 55, but is not pressed by lever

55 enough to close normally open limit switch 53. When cam roller 94 depresses cam bar 54 against the urging of spring 116, hinge 56 is also depressed to the point where notch 117 at one end of cam bar 54 rests against fulcrum 110, and notch 118 at the other end of the cam bar rests against fulcrum 112. Cam bar 54 is shown in this position in Figures 8 and 14B.

Depression of the upper end of cam lever 55 (which is rotatably attached to hinge 56) causes the bottom end of the cam lever to be raised. As the bottom end of cam lever 55 is raised, this pushes wheel 57 and causes the arm on which the wheel is borne to be rotated, thus actuating hoist switch 53.

Cam bar 54 is shown in Figure 9 in its uppermost position just before it is struck by cam roller 94. Figures 12B and 14B show how cam roller 94 depresses cam bar 54 when the roller rides upon the bar.

Figure 16 shows in plan view how cargo pallet 46, upon approaching cargo hoist 49 from the direction of the cargo accumulation station at which the pallet was loaded with air cargo, will have its cam roller 94 and guide roller 95 directed in the correct path by guide chutes 92 and 93, respectively. Cargo pallet 46 rides upon elevating members 51 and 52. Cam roller 94 trips cam bar 54, and actuates hoist switch 53 as explained above. This causes cargo hoist 49 to raise pallet 46 into the position shown in plan in Figure 16.

Figures 17 and 18 are views of cargo hoist 50, which is at the outermost plane loading station of the system shown in Figure 1. Figure 17 shows how guide roller 104 on cargo pallet 47 is guided along the correct path by guide chute 130 on elevating member 131 of cargo hoist 50. As shown in Figure 18, guide chute 132 occupies a corresponding position on elevating member 133 on the opposite side of hoist 50. Cam bar 102 on elevating member 133 of hoist 50 is of similar construction to cam bar 54 on hoist 49.

Personnel platform 134 is shown in Figure 18 as folded back on hinges 135 to be out of the way of cargo pallet 47 as it rides upon elevating members 131 and 133. The personnel platform is also shown folded back in end view (as seen from the direction of arrival of cargo pallet 47) in Figure 20. When cargo hoist 50 is used without cargo pallet 47, personnel platform 134 may be folded over into the position shown in broken line in Figure 19 to increase the area of the platform by about one half.

Figure 18 shows how cam roller 100 of cargo pallet 47 rolls through guide chute 132 on elevating member 133 and from there onto cam bar 102. Depression of cam bar 102 actuates hoist switch 141, in the same manner as hoist switch 53 on cargo hoist 49 was actuated by cam roller 94 of cargo pallet 46. Upright members 142 and 143 of cargo hoist 50, and corresponding upright members 142a and 143a on the opposite side of the hoist, are then raised from the down or collapsed position toward the vertical position and this raises elevating members 131 and 133 with cargo pallet 47 upon them.

Figure 21 gives a plan view of elevating member 144 of cargo hoist 48, which is located at the innermost plane loading station of the system shown in Figure 1. Cam roller 101 of cargo pallet 45 will be guided through guide chute 145 as it approaches the hoist, and will ride from the chute upon cam bar 103. Cam bar 103 is arranged with respect to its associated hoist switch for cargo hoist 48 in a manner similar to cam bar 54 of hoist 49 and cam bar 102 of hoist 50.

Consideration of Figures 9, 16, 18 and 21 discloses how the cam rollers of the various cargo pallets 45, 46 and 47 selectively operate the hoist switch means of their associated cargo hoists. The elevating members of each cargo hoist are in effect divided into lanes: three each at hoists 48 and 49, and, for convenience, two lanes at hoist 50. The cam rollers at the front of each cargo pallet (and the corresponding rollers directly behind

them) are located so that they are all at a characteristic distance from the longitudinal axis of the pallet for each of the three pallets. The rollers are so aligned that as their pallet is propelled over the elevating members of the cargo hoists the rollers for a given pallet will always pass through the same lane on those elevating members. The cam roller and the roller trailing it mounted on cargo pallet 47, for example, always ride in the outermost lane on the cargo hoists. The corresponding rollers on pallet 46 always ride in the middle lane on the cargo hoists. The same rollers on pallet 45 always ride in the innermost lane.

Since the cam bars on cargo hoists 48 and 49 are in the middle and innermost lanes, cargo pallet 47 passes over those hoists without having its cam roller 100 actuate a hoist switch. It is not until pallet 47 reaches the outermost cargo hoist 50 that cam roller 100 finds cam bar 102 in its path.

Similarly, pallet 46 passes over cargo hoist 48 without having its cam roller 94 actuate the hoist switch of that hoist. However, when pallet 46 reaches cargo hoist 49, cam roller 94 depresses cam bar 54 and causes the hoist to raise its pallet.

In the same manner, cam roller 101 will depress cam bar 103 as soon as it reaches cargo hoist 48.

As already explained, when the cam bar of a cargo hoist is depressed, the hoist is caused to lift the cargo pallet off conveyor belt 40. The cam bar is permitted to be pushed down an appreciable distance below the top of the elevating member on which it is carried, as is shown in Figure 19 for cam bar 102 and elevating member 138 of cargo hoist 50.

Simultaneously, as shown in Figures 17, 18 and 22, guide roller 104 at the front of the opposite side of cargo pallet 47 is caused to roll down inclined trough 150 into level trough 151, both in elevating member 131. As a result, the forward movement of cargo pallet 47 is continued, despite the breaking of frictional engagement between conveyor belt 40 and the pallet, until the pallet has moved into a position near the middle of the cargo hoist.

In Figures 19 and 22, cargo pallet 47 has not yet reached its position of forwardmost roll, since guide roller 104 has presumably not yet come to rest in level trough 151, as is the case in Figure 17. In Figure 16, cargo pallet 46 has come to rest in the position it occupies while being raised by hoist 49, with its guide wheel 95 having coasted down incline 152 into depressed trough 153.

Conveyor structure

Figure 13 gives a cross sectional view of conveyor structure 37. The sectional view is taken along the line 13—13 in Figure 24. As will be seen from Figure 1, line 13—13 might be indicated at one of many places (except the curved section of the conveyor) along the entire length of conveyor 37.

Framework 160 carries support rollers 161 and return rollers 162. The upper or conveying portion 163 of conveyor belt 40 rides upon support rollers 161. The lower or return portion 164 rides upon idler rollers 162. Framework 160 also carries tracks 41 on either side of the conveyor belt.

It has already been explained that cargo hoists 48, 49 and 50 may be moved limited distances along the axis of conveyor 37. Uprights 165 and cross bars 166 of conveyor framework 160 present limits upon the extent to which the cargo hoists may be so moved.

Since axles 65 and 66 and platform 67 of cargo hoist 49, for example, extend across from base member 61 to 61a, these three transverse members will all require clearance in order for the hoist to be moved any substantial distance. This may be best seen in Figures 6, 7 and 14A. With platform 67 and axle 66 straddling a particular upright 165 of conveyor structure 160 with one of them on either side of the upright, hoist 49 may be moved

a certain distance forward and backward. This distance is increased by removing the lower portions of uprights 165 and the accompanying cross bar 166 in order to permit clearance underneath the remaining portions 167 of the upright. The clearance is best seen in Figures 9 and 12A, where it is seen that the hydraulic system carried by platform 67 is able to pass under return roller 162 and portions 167 of uprights 165. The distance which cargo hoist 49 may be moved along conveyor 37 may be further increased, if desired, by splitting front axle 66 of the hoist into two short axles each of which is entirely outside conveyor structure 160. This embodiment is shown in Figure 8.

Hydraulic system

The hydraulic system by which cargo hoist 49 is operated is shown in plan view in Figure 23, in end elevation in Figure 12A, and in side elevation in Figure 14A. The major part of the hydraulic system for hoist 49 is mounted on platform 67 which extends between base members 61 and 61a.

Referring now to Figure 23, electric motor 200 drives hydraulic pump 201 through flexible coupling 202. Input pipe 203 of pump 201 is connected with hydraulic oil reservoir 204. Reservoir 204 is filled with oil through pipe 205, provided with a breather cap 206.

Output pipe 207 of pump 201 is connected with 4-way valve 208 through relief valve 209 and connecting pipe 210. Relief valve 209 is connected through pipe 211 with return line 212 leading back to oil reservoir 204. The relief valve is adjusted for a predetermined maximum pressure. If the pressure in line 207 rises above this figure, sufficient oil is diverted through lines 211 and 212 back to the reservoir to reduce the pressure to the predetermined maximum.

Valve 208 is a 4-way valve of conventional type which connects input pipe 210 with return line 212 when no hydraulic pressure is to be applied to hydraulic rams 60 and 60a, with output line 213 when pressure is to be applied to the top end of the rams, and with output lines 225 when pressure is to be applied at the bottom end of the rams.

Line 213 leads from valve 208 to 4-way fitting 214 and from there to T-joint 215. T-joint 215 branches out on one side to check valve 216 and on the other to check valve 217. Line 218 leads from check valve 217 through flexible tubing 219 to the top side of the cylinder of hydraulic ram 60. Line 220 leads from check valve 216 in the same way through flexible tubing 221 to the top 50 side of hydraulic ram 60a on the opposite side of cargo hoist 49.

Line 225 leads from valve 208 to 4-way fitting 226 and beyond that to T-joint 227. T-joint 227 is connected on one side to check valve 228 and on the other to check valve 229. Line 230 leads from check valve 228 through flexible tubing 231 to flow control valves 232 and 233, and then to the bottom side of the cylinder of hydraulic ram 60. Line 234 leads in the same way from check valve 229 through flexible tubing 235 to flow control valves 236 and 237, and from there to the bottom side of the cylinder of hydraulic ram 60a on the opposite side of cargo hoist 57.

Pilot lines 240 and 241 lead from 4-way fitting 214 to check valves 228 and 229, respectively. In the same way, pilot lines 242 and 243 lead from 4-way valve 226 to check valves 216 and 217, respectively. Each of the check valves 228, 229, 216 and 217 is of conventional construction. The valves are adapted to be actuated by hydraulic pressure from pilot lines 240, 241, 242 and 243, respectively, without the flow of any fluid through the pilot lines into the check valves. The valves normally permit flow of fluid in one direction only, and when actuated by application of hydraulic pressure through the associated pilot line will permit oil flow only in the reverse direction.

Application of pressure through line 213, 4-way fitting 214 and pilot lines 240 and 241 causes check valves 228 and 229 to permit oil flow only in the direction away from rams 124 and 124a, respectively. This bars application of hydraulic pressure through those check valves to the bottom sides of hydraulic rams 60 and 60a.

Similarly, application of pressure through line 225, 4-way fitting 226 and pilot lines 242 and 243 causes check valves 216 and 217 to permit oil flow only away from rams 60a and 60, respectively. This bars application of fluid pressure to the top side of hydraulic rams 60 and 60a.

Bleed line 244 is the only other connection to 4-way valve 208. This line leads from valve 208 back to oil reservoir 204. It carries back to the reservoir any internal leakage of oil which may appear in valve 208.

Motor 200 of the hydraulic system is energized by means of the circuit shown in Figure 27 and described below in this specification. 4-way valve 208 is operated by a system of push buttons which are included in the same circuit.

When motor 200 drives pump 201, hydraulic pressure is applied either at the bottom or top ends of hydraulic rams 60 and 60a, depending upon the condition of valve 208. When 4-way valve 208 connects input line 210 with return line 212 leading to oil reservoir 204, pump 201 merely circulates oil through the system without applying any hydraulic pressure to rams 60 and 60a.

When input line 210 is connected through 4-way valve 208 with output line 225, valve 208 at the same time connects line 213 with return line 212. This applies hydraulic pressure to the bottom end of hydraulic ram 60 through T-joint 227, valve 228, line 230, flexible tubing 231, and flow control valves 232 and 233. At the same time, the upper end of hydraulic ram 60 is connected through flexible tubing 219, line 218, check valve 217, T-joint 215 and line 213 to 4-way valve 208 and from there through return line 212 back to oil reservoir 204. Application of increased hydraulic pressure at the bottom end of ram 60, with all hydraulic pressure removed from the top end, forces piston 62 out of the cylinder of ram 60.

A similar application of hydraulic pressure at the bottom of hydraulic ram 60a and return of fluid from the top end of ram 60a back to reservoir 204 causes piston 62a to be forced out of the cylinder of that hydraulic ram.

When 4-way valve 208 connects input line 210 with output line 213 it also connects line 225 with return line 212. This produces the opposite result from that just described. Hydraulic pressure is then applied to the top end of hydraulic ram 60 through T-joint 215, check valve 217, line 218 and flexible tubing 219. At the same time, the pressure in output line 213 acts through 4-way coupling 214 and pilot line 240 to actuate check valve 228 to permit oil to flow from the bottom end of hydraulic ram 124 through flow control valves 233 and 232, flexible tubing 231, line 230, T-joint 227, line 225 and return line 212 back to oil reservoir 204. The application of hydraulic pressure at the top of ram 60 and flow of oil from the bottom of the ram back to the oil reservoir cause piston 62 to be forced back into the cylinder of hydraulic ram 60. At the same time, a similar result occurs on the opposite side of hoist 49 with hydraulic ram 60a.

It is essential that elevating members 51 and 52 of cargo hoist 49 rise and fall at the same rate, in order to keep those two members always at the same height. Otherwise cargo pallet 46 would be tipped sidewise in one direction or the other, and might damage plane 36 or in extreme cases might fall off the hoist and damage the baggage or the personnel handling the baggage.

Uniform rate of rise and fall of elevating members 51 and 52 is produced by keeping equal the rates at which pistons 62 and 62a are extended from and forced back into the cylinders of hydraulic rams 60 and 60a, respectively. The control of the rates of movement of pistons 62 and

62a is accomplished by use of flow control valves 232, 233, 236 and 237.

Each of the four valves 232, 233, 236 and 237 permits a free flow of oil in one direction and regulates accurately the maximum rate at which oil may flow through the valve in the opposite direction. Valves 232 and 233 are arranged so that the direction in which flow control valve 232 controls the maximum volume of oil that may pass through it in a given time, and the direction in which valve 233 has the same effect, are opposite to each other. The result is that the volume of oil passing through flow control valves 232 and 233—and thus through the cylinder of hydraulic ram 60—in either direction during a given period never rises above a predetermined maximum amount. Generally the maximum permitted rate of flow is the same in both directions, but the essential thing is that in a given direction the maximum possible rate of flow is always equal for the two rams on opposite sides of the hoist.

20 In the hydraulic system shown, pump 201 has an output rate greater than the combined rates of maximum flow in a particular direction permitted by flow control valves 232 and 233 on one side of cargo hoist 57 and flow control valves 236 and 237, connected with hydraulic ram 60a, on the opposite side of the hoist. Valves 236 and 237 have the same characteristics as valves 232 and 233, respectively. Thus the rate of flow to hydraulic rams 60 and 60a is always the maximum permitted by the flow control valves, and is always the same for corresponding ends of rams 60 and 60a.

Pistons 62 and 62a occupy the same relative positions in rams 60 and 60a when cargo hoist 49 is in its down or collapsed position. In this position the upper end of each piston is at the same height as the upper end of the other piston. The performance characteristics of each hydraulic ram and its piston are also the same. As a result, flow of equal amounts of fluid under pressure into the bottom ends of rams 60 and 60a to extend pistons 62 and 62a will extend the pistons so that their upper ends are always at the same height. This keeps upright members 63 and 63a and the rest of the frames which support elevating members 52 and 51, respectively, in the same relative positions at all times while the elevating members are being raised.

45 For the same reasons, elevating members 51 and 52 are maintained at the same height as they are lowered when pistons 62 and 62a are forced back into the cylinders of rams 60 and 60a, respectively, by flow of equal amounts of fluid under pressure at the top ends of the two rams.

Cargo pallet

In Figure 24, cargo pallet 46 is shown being propelled by conveyor belt 40 along a section of conveyor 37 which may be, for example, alongside plane 36. Upper or conveying portion 163 of the conveyor belt rides upon support rollers 161. Lower or return portion 164 of the belt rides upon idler rollers 162.

The superstructure or body of cargo pallet 46 is comprised of base 270, uprights 271 and 272 on one side, uprights 271a and 272a on the other, and horizontal panels 273 extending around the pallet and supported by the uprights. Horizontal panels 273 on the side of the pallet next to plane 36 are preferably removable, as indicated in Figure 1, for convenience in loading and unloading the pallet. Base 270 carries rear axle 274 and front axle 275 upon which are mounted rear wheels 276 and 276a, and front wheels 277 and 277a, respectively. Wheels 276 and 277, on the right side of cargo pallet 46 as seen in Figure 24, are omitted for clarity in that drawing. Axles 274 and 275 are pivotally mounted on the bottom side of base 270 by a means shown in greater detail in Figure 26.

In Figure 26, the various parts of the apparatus by which axle 274 and traction plate 267 are suspended from the base of cargo pallet 46 are shown in an exploded side view. Axle 274 is welded to channel 278,

which is in turn welded to upper plate 279. Plate 279 carries shaft 280 rising vertically above it. Bearing 281, with rotatable member 281a, is attached to base 270 of the cargo pallet, and vertical shaft 280 is connected to rotatable member 281a by a bolt or cotter pin passing through corresponding holes in the two members. This arrangement permits axle 274 to be rotated, in the horizontal plane, with respect to the longitudinal axis of the cargo pallet.

Traction plate 267 is also arranged to rotate in the horizontal plane with respect to axle 274. Vertical cylinders 282 and 282a are welded to the bottom side of plate 279, one near the leading edge of the plate and one near the trailing edge. Pistons 283 and 283a are slideably engaged in cylinders 282 and 282a, respectively, with their upper ends passing through plate 279 and secured against complete withdrawal from the cylinders by cotter pins or similar means. Coil springs 284 and 284a are arranged about the outside of the cylinders, pressing against plate 279 at their upper ends. At their bottom ends, the springs press against circular piston plate 285, to which are welded the bottom ends of pistons 283 and 283a. When compressed, springs 284 and 284a continuously urge piston plate 285 downward from upper plate 279. This provides the spring loading for traction plate 267. Traction plate 267 is carried by circular backing plate 286, which is rotatably connected to piston plate 285 by means of traction plate shaft 287. Ball bearings 288 are confined between piston plate 285 and backing plate 286, riding within channels 289 in those plates. Channels 289 are aligned with each other vertically and are concentric with circular plates 285 and 286 themselves.

When assembled, these parts have the appearance shown in Figure 24 in side elevation and in Figure 12B in end elevation. As seen, the arrangement of parts provides a traction plate 267 which is continuously urged by coil springs 284 and 284a against conveyor belt 40 while cargo pallet 46 rides with its wheels 276, 276a, 277 and 277a upon tracks 41. At the same time, the arrangement of parts is such that when cargo pallet 46 is raised by hoist 49 so that the frictional engagement between traction plate 267 and conveyor belt 40 is broken, plate 267 hangs suspended in midair from base 270.

Because shaft 280 and member 281a are rotatable in bearing casing 281, axle 274 (split at the center as seen in Figure 12B to accommodate the traction plate assembly) can rotate in a horizontal plane carrying with it wheels 276 and 276a. As seen in Figure 12B, wheel 276a is flanged, for a purpose to be explained below. Small rollers 268 are rotatably mounted above axle 274 at either end upon brackets attached to channel 278, to provide an additional support between axle 274 and base member 270 when the axle rotates with respect to cargo pallet 46.

As shown in Figure 12B, cargo pallet 46 carries near its left front corner cam roller 94 and near its right front corner guide roller 95. The purpose of rollers 94 and 95 has been explained above in connection with the discussion of the hoist switch for cargo hoist 49. Corresponding rollers are positioned at the rear of the pallet.

Traction plate 290 is suspended from the front axle assembly of cargo pallet 46 in a manner similar to the suspension of traction plate 267 at the rear of the pallet. When cargo pallet 46 moves along tracks 41 in a straight portion of conveyor 37, it is propelled by frictional engagement between the upper surface of conveyor belt 40, for example, and the bottom surface of traction plates 267 and 290, which are urged by their loading springs against the surface of the belt.

In the embodiment shown, pallet 46 must be propelled not only along a straight section of rails 41 where straight conveyor belts such as 38 and 40 operate, but it must also be propelled across the gap between one endless conveyor belt and an adjacent endless conveyor belt, and must

in addition be propelled around the curve of conveyor belt 39. Figure 2 shows the two gaps and the curved section of conveyor 37 which occur along the path of cargo pallet 46 as it is propelled from the cargo accumulation station out to hoist 49.

Referring again to Figure 24, it is seen that leading traction plate 290 may be pushed out over the gap between adjacent conveyor belts without breaking the frictional engagement between spring loaded traction plate 267 and the upper surface of the conveyor belt. If cargo pallet 46 is passing from conveyor belt 38 to 39, for example, the continued frictional engagement of plate 267 with belt 38 will push the pallet along rails 41 until spring loaded traction plate 290 attains a firm frictional engagement with the upper surface of conveyor belt 39. The frictional engagement between plate 290 and 39 will continue to propel cargo pallet 46 in a forward direction, even when traction plate 267 has momentarily broken its frictional engagement with conveyor belt 38. As cargo pallet 46 proceeds forward, spring loaded traction plate 267 again attains frictional engagement with a conveyor belt, this time belt 39. Cargo pallet 46 is propelled across the gap between conveyor belts 39 and 40 in the same manner.

As cargo pallet 46 is propelled around the curve by conveyor belt 39, rotatable axles 275 and 274 are free to turn to permit the body of the pallet to turn at a different rate than the axles. This is necessary because with the sharp curvature of the curved section of conveyor 37 there is a significant difference in the direction in which cargo pallet 46 faces while on the curve and the directions in which the leading and trailing axles face.

To assure that leading axle 275 will tend to face in the proper direction to turn around the curve when cargo pallet 46 passes from conveyor belt 38 onto conveyor belt 39, inner wheel 277a of the cargo pallet is flanged. When cargo pallet 46 leaves the straight section of tracks 41 which flank conveyor belt 38, and enters upon the curved section of the tracks flanking curved conveyor belt 39, inner pallet wheel 277a is caused to drag somewhat by the frictional resistance between the wheel flanges and the track. This helps turn axle 275 counterclockwise as seen in the lower right hand corner of Figure 25, to go around the curve. Wheel 277 at the outer end of axle 275 is not flanged, and so it simply follows along the outer track of the pair of tracks 41.

As shown in Figure 16, the outer end of axle 275 is rotatably connected to rigid bar 291, which in turn is rotatably attached at its other end to the inner end of axle 274. This is also seen in Figure 25. As the inner end of axle 275 is caused to drag by the flanges on wheel 277a and the outer end of axle 275 is thus forced forward, rod 291 pulls the inner end of trailing axle 274 forward and this in turn pushes the outer end of axle 274 back. This places both leading axle 275 and trailing axle 274 in proper position for carrying cargo pallet 46 around the curve.

As will be seen from Figure 25, axles 274 and 275 are turned in a similar fashion when cargo pallet 46 moves around the curve in the opposite direction. When pallet 46 moves in a clockwise direction as seen in Figure 25, flanged wheel 276a drags somewhat, outer wheel 277 on axle 275 is forced backward by action of rod 291, and flanged wheel 277a is pushed forward somewhat. Both axle 274 and 275 are then facing in the proper direction to make the turn around the curve in the conveyor belt.

As cargo pallet 46 is just entering or leaving the curved section of tracks 41, the direction in which traction plate 267 or 290 faces may be different from the direction of both the pallet and the rotatable axles. This occurs because (as shown at the upper left hand side of Figure 25) the automatic turning of axles 274 and 275 to accommodate for the curve in tracks 41 takes place simultaneously. As axle 274 first enters upon the curve while pallet 46 is moving toward the cargo accumulation

center, for example, axle 274 turns with the curve, and so does traction plate 267. At the rear end of the pallet, however, axle 275 is caused by the automatic operation of rod 291 to turn prematurely. Axle 275 is already positioned for the curve, while that end of the pallet still rides upon the straight section of tracks 41. Rotation of traction plate 290 upon ball bearings 288 continues the traction plate in its same frictional engagement with conveyor belt 40, rather than forcing the plate to skew around upon the belt when axle 274 is turned as just described.

When cargo pallet 46 is lifted off tracks 41 by hoist 49, as shown in Figure 16, axles 274 and 275 must be kept at right angles to the longitudinal axis of the pallet in order that the wheels carried by those axles will be in proper position for riding upon tracks 41 when the pallet is returned to its position upon the tracks. Stops 292 and 292a are attached to base member 270 in positions which will bring axles 274 and 275 at 90° to the axis of the pallet when the axles are pressed against the stops. Coil spring 293 is connected at one end to base member 270 and at the other to the end of axle 274 opposite that at which rod 291 is attached. The tension of spring 293 pulls the end of rotatable axle 274 to which it is attached toward the center of the pallet, and against stop 292. This brings axle 274 into position at 90° to the axis of the pallet. The end of axle 274 opposite stop 292 is automatically pulled away from the center of the pallet by action of spring 293, and the action of rod 291 at the same time automatically pulls the diagonally opposite end of axle 275 against stop 292a. Axles 274 and 275 are by this means automatically kept properly positioned while cargo pallet 46 is lifted off tracks 41. Coupling 291a is provided to adjust the length of rigid rod 291 whenever necessary to keep axle 275 parallel to axle 274 when the latter is pulled snugly against stop 292.

Electrical circuit for actuating hydraulic systems of hoists

Figure 27 gives a diagram of the electrical circuit by means of which the hydraulic systems of cargo hoists 48, 49 and 50 are actuated. It also includes a circuit diagram of the electrical interlock system by means of which each cargo pallet 45, 46 and 47 is prevented from leaving its respective station at plane 36 to go back to the cargo accumulation station unless every other cargo pallet between the pallet in question and the cargo accumulation station has already started back toward that station.

In Figure 27, push button switch 300 is used for manual raising and lowering of cargo hoist 48. Similar switches 301 and 302 are used for manual operation of hoists 49 and 50, respectively. (As pointed out above, cargo hoist 50 occupies the outermost position near the nose of plane 36, hoist 49 occupies the middle position, and hoist 48 occupies the innermost position nearest the cargo accumulation station.) Electrically operated relays 303, 304 and 305 are employed in the circuits through which power is applied to run the electric motors of the hydraulic systems of hoists 48, 49 and 50, respectively. Three-phase electrical motor 200 is the motor carried, in the manner shown in Figures 9, 12A, 14A and 23, upon platform 67 of cargo hoist 49. Similar motors 306 and 307 are the drive means for the hydraulic pumps of cargo hoists 48 and 50, respectively.

Solenoid 310 operates 4-way valve 208 (shown in Figure 23) of the hydraulic system for cargo hoist 49. Solenoids 311 and 312 perform a similar function in the hydraulic systems of cargo hoists 48 and 50, respectively.

Limit switch 53 is the hoist switch of cargo hoist 49. Limit switches 313 and 314 are the hoist switches for cargo hoists 48 and 50, respectively. Limit switch 315 is carried upon base member 61 of cargo hoist 49, as shown in Figure 14A. Limit switch 316 is carried in a similar position upon cargo hoist 48. Limit switch 317

on cargo hoist 50 corresponds to switches 315 and 316, and limit switch 318 is an additional switch employed because of the extra manual control on that hoist for bringing it down only part way when desired.

5 Other components of the circuit shown in Figure 27 will be identified as the circuit is described.

Closing of a manually operated switch (not shown) applies three-phase alternating voltage to power lines 330, 331 and 332, to supply the electrical power for 10 the hydraulic systems of cargo hoists 48, 49 and 50. As cargo hoist 49 is the hoist which is most completely shown and described in this specification, operation of the hydraulic system of that hoist will be discussed first. As has been explained above, the elevating mechanism 15 of hoist 49 is actuated only by cargo pallet 46. In this description, therefore, cargo pallet 47 is considered already to have passed beyond cargo hoist 49.

The voltage on power line 330 is applied to one side 20 of solenoid 338 to relay 304 through line 333, contact 334 of relay 304, lead 335, and overload switch 336, which is normally held closed by heater coil 337. The other side of solenoid 338 is connected to a second overload switch 339, which is normally held closed by heater coil 340.

25 The voltage on power line 332 is applied to terminal 344 of limit switch 315 through line 341, contact 342 of relay 304, and lead 343. When switch 315 is closed, terminal 344 is connected with its opposite terminal 345, which in turn is connected with terminal 346 of limit switch 315.

30 Limit switch 315, as shown in Figure 14A, is normally biased open. However, when bracket 348 mounted on upright 63 of cargo hoist 49 swings downward while the hoist is being lowered into its collapsed position, the bracket reaches a predetermined height at which it strikes switch wheel 349 and closes limit switch 315. In the embodiment shown, this occurs when elevating members 31 and 52 of cargo hoist 49 have reached a point in their descent which is about a foot, or slightly more, above 35 conveyor belt 40. Whenever upright 63 and bracket 348 are in this position or lower, the switch member connecting terminals 344 and 345 of limit switch 315 is held closed. Thus switch 315 is always closed whenever cargo hoist 49 is in its down position, as when it is awaiting arrival of its associated cargo pallet.

35 When hoist switch 53 is closed by arrival of cargo pallet 49 at the hoist, this connects terminal 346 of the switch to opposite terminal 347. Terminal 347 is connected through line 350 to overload switch 339 and solenoid 338. Thus, so long as limit switch 315 is closed, the closing of 40 hoist switch 53 places the potential difference between power lines 332 and 330 across solenoid 338.

45 Energizing of coil 338 closes all the contacts in relay 304. As a result, voltage is applied to three-phase electrical motor 200 from power line 330 through lead 333, contacts 334 and 360 of relay 304, and heater coil 337. At the same time, voltage is applied to the motor from power line 331 through lead 361 and terminals 362 and 363 of relay 304. Similarly, voltage is applied from 50 power line 332 through lead 341, terminals 342 and 364 of relay 304, and heater coil 340. Arrival of cargo pallet 46 at cargo hoist 49 thus starts motor 200.

If during operation of the hydraulic system an overload is ever imposed upon motor 200 through either 55 heater coil 337 or 340, the overload heater coil will open overload switch 336 or 339, respectively. Current will immediately cease to flow through solenoid 338, relay 304 will open, and operation of motor 200 and the hydraulic system will cease.

60 The closing of hoist switch 53 not only applies a potential difference across solenoid 338, but in addition across coil 371 of solenoid 310 of 4-way valve 208. As has been pointed out above, terminal 346 of hoist switch 53 is connected with power line 332 whenever switch 315 is closed. Closing switch 53 connects terminal 346 with

contact 365 of the same switch. Contact 365 is connected with one side of coil 371 through line 366, contacts 367, 368 and 369 of push button switch 301, and line 370. The other side of coil 371 is connected through line 372 with terminal 334 of relay 304 and from there through line 333 to power line 330.

Application of this voltage to coil 371 of solenoid 310 places 4-way valve 208 in condition to cause hydraulic pressure from pump 201 to be applied (in the manner explained above) through the hydraulic system of cargo hoist 49 to the bottom end of hydraulic rams 60 and 60a. As a result, cargo hoist 49 raises cargo pallet 46 off conveyor belt 40.

The automatic raising of cargo pallet 46 continues until the pallet reaches the predetermined height at which bracket 348 releases switch wheel 349 and permits limit switch 315 to resume its normal open position. Operating switch 315 breaks the connection between power line 332 and contact 346 of switch 53, so removes the potential difference from solenoid 371 of relay 310. This permits 4-way valve 208 to return to its normal condition, in which input pipe 210 is connected through the valve to return pipe 212 leading to oil reservoir 204. No additional hydraulic pressure is applied thereafter to the bottom of rams 60 and 60a, and thus the raising of the cargo pallet is automatically stopped.

At this juncture cargo hoist 49, with cargo pallet 46 upon it, will have been raised to about the predetermined height mentioned above—about one foot, or a little more. With cargo holds located at about the height shown in Figure 1 for holds 33 and 34 of plane 36, it is desirable to raise the cargo pallet still higher toward the hold. With a cargo hold located at about the height shown for hold 35 in Figure 1, the cargo hoist will generally be elevated practically to its full extension.

Additional raising of the cargo hoist and the cargo pallet above the height to which they rise automatically is accomplished by manual operation of push button switch 301. Power line 332 is connected through lead 341, terminal 342 of relay 304, line 343, and lead 373 to terminal 374 of switch 301. So long as the "Stop" button is not pressed, terminal 374 is connected with terminal 375, which in turn is connected with terminals 376, 377 and 378 of relay 301. If the "up" button is pressed, a connection is made between terminals 378 and 369 of relay 301, and one side of coil 371 of solenoid 310 of 4-way valve 208 is thereby connected with power line 332. Since the other side of coil 371 is connected with power line 330 by means previously described, pressing the "up" button energizes coil 371 and places 4-way valve 208 in condition to permit application of hydraulic pressure to the bottom end of hydraulic rams 60 and 60a.

Pushing the "up" button also establishes a connection between terminals 377 and 379 of switch 301. Leads 380 and 350 connect terminal 379 with solenoid 338 of relay 304. This imposes the potential difference between power line 332 and power line 330 across solenoid 338, and actuates relay 304. Actuating relay 304 closes all the contacts of that relay and applies three-phase alternating voltage to motor 200. Thus, pushing the "up" button of switch 301 energizes motor 200 simultaneously with the actuation of 4-way valve 208.

As a result, hydraulic pressure is applied to the bottom side of rams 60 and 60a of cargo hoist 49, and elevating members 51 and 52 of the hoist are caused to rise. This raises cargo pallet 46. Hoist 49 continues to raise cargo pallet 46 so long as the "up" button is held closed by the operator. As soon as the pallet has been raised to the desired height, the operator releases the "up" button and the two circuits through solenoid 338 of relay 304 and coil 371 of relay 310 are broken. The operation of motor 200 immediately stops, and 4-way valve 208 returns to its neutral condition.

After all the cargo has been transferred from cargo

pallet 46 into cargo hold 34 of plane 36, the operator may lower cargo hoist 49 manually (if the interlock circuit described below does not prevent this) to drop cargo pallet 46 into a position where traction plates 267 and 290 resume their frictional engagement with conveyor belt 40 and the pallet is propelled back on tracks 41 toward the cargo accumulation center. Pressing the "down" button breaks the connection between terminals 367 and 368 of switch 301, and also connects terminals 376 and 390 of the same switch. Terminal 390 is connected through lead 391 to solenoid 392 of timer 393.

Timer 393 may be a conventional type which is adjustable to provide the desired period of electrical contact between its terminals. The time selected should be long enough to permit cargo hoist 49 to lower cargo pallet 46 from the highest possible position of that pallet to a point where frictional engagement is established with conveyor belt 40 and the cargo pallet has been rolled off elevating members 51 and 52 onto tracks 41. During this period, timer 393 acts to keep the hydraulic system of cargo host 49 continuously operative to drive the hoist down and hold it down despite the fact that—from the time hoist 49 descends to the height at which limit switch 315 is closed until a short time after conveyor belt 40 establishes contact with traction plates 267 and 290 and the pallet first starts to move off the hoist—both host switch 53 (because cam roller 94 continues to depress cam bar 54) and limit switch 315 are closed. Ordinarily, of course, when switch 53 is closed while limit switch 315 is also closed, cargo hoist 49 automatically raises pallet 46 into the air.

As already explained, when the "stop" button is not pressed, terminal 375 of switch 301 is connected to power line 332 through contact 374 of relay 301, lines 373 and 343, terminal 342 of relay 304, and line 341. Terminal 375 is connected with terminal 376 of the same switch, and, as pointed out above, when the "down" button is pressed the latter terminal is connected with one side of solenoid 392 of timer 393. The other side of the solenoid is connected by line 394 to terminal 395 of limit switch 316 associated with cargo hoist 48. This provides an interlock circuit between hoists 49 and 48, as will be explained in more detail below. When limit switch 316 is closed, terminals 395 and 396 of that switch are connected. Terminal 396 is connected through lines 397 and 372, terminal 334 of relay 304, and line 333 to power line 330. It is seen that when the "down" button is pressed the potential difference between power lines 332 and 330 is impressed across solenoid 392 of timer 393, thus closing the contacts of the timer.

Terminal 375 of push button switch 301 is connected through lead 401 with terminal 402 of timer 393. With the contacts of the timer closed, terminal 402 is connected with terminal 403 and through lines 404 and 350 to one side of solenoid 338 of relay 304. Since the other side of solenoid 338 is connected with power line 330, relay 304 is energized and motor 200 is started.

At the same time, 4-way valve 208 is actuated to cause hydraulic pressure to be applied to the top end of the cylinders of rams 60 and 60a. Terminal 402 of timer 393 is connected with terminal 405. So long as the contacts of timer 393 remain closed, terminal 405 is connected with terminal 406 of the timer. Lead 407 connects terminal 406 to one side of coil 408 of solenoid 310. Voltage from power line 330 is applied to the other side of coil 408 through line 333, terminal 334 of relay 304, and line 372. The energizing of coil 408 activates 4-way valve 208.

As long as timer 393 remains closed, voltage is applied across motor 200 and coil 408, and cargo hoist 49 proceeds downward to its collapsed position, where it is held by the hydraulic system of the hoist. Of course, if the "stop" button of push button switch 301 is pressed,

this will break the circuits which apply the voltage of power line 332 to solenoid 338 and to coil 408 of solenoid 301. This will stop operation of hydraulic rams 60 and 60a. Then, to start the hoist down again, the "stop" button must be released and the "down" button pressed.

The operation of cargo hoist 50, at the outermost plane loading station near the nose of plane 36, is similar to that of cargo hoist 49, but with some additions because of the special conditions at that plane loading station. Relay 305 of cargo hoist 50, for example, is the same in construction and operation as relay 304 of hoist 49, with power from power lines 330, 331 and 332 being applied to relay 305 through lines 420, 421 and 422, respectively. Lines 423, 424 and 425 connect the other side of relay 305 to three-phase electrical motor 307.

Alternating voltage from power line 330 is applied through line 420 to one side of solenoid 426 of relay 305 in series with other elements similar to those contained in relay 304. Alternating voltage from power line 332 is applied through line 422, terminal 431 of relay 305 and line 432 to terminal 433 of push button switch 302. So long as the "stop" button of switch 302 is not pressed, terminal 433 is connected with terminal 434. Terminal 434 is connected by lead 435 to terminal 436 of limit switch 317. With limit switch 317 closed, terminal 436 is connected with terminal 437 of switch 317. Terminal 437 is connected with terminal 438 of hoist switch 141. When hoist switch 141 is closed by the arrival of cargo pallet 47 at cargo hoist 50, terminal 438 is connected with terminal 430. This puts the voltage of power line 332 on the other side of solenoid 426—through lead 429, terminal 428 of relay 319, and lead 427—and closes relay 305, causing motor 307 to be energized.

Closing hoist switch 141 also connects terminal 438 with contact 439 of that switch. This applies the voltage of power line 332 through line 440 to one side of coil 441 of solenoid 312. The alternating voltage of power line 330 is applied to the other side of coil 441 through line 420, terminal 442 of relay 305, and line 443. This actuates the 4-way valve of the hydraulic system of cargo hoist 50 to cause hydraulic pressure to be applied at the bottom end of the hydraulic rams of that hoist.

Thus the arrival of cargo pallet 47, and the resulting closing of hoist switch 141, automatically cause elevating members 131 and 132 of cargo hoist 50 to be raised. Elevating members 131 and 132 carry pallet 47 upward with it. The automatic elevation of cargo pallet 47 continues until limit switch 317 opens at a predetermined height, in the same manner as limit switch 315 of cargo hoist 49 opened after cargo pallet 46 had been raised to a predetermined height. Further raising of cargo pallet 47 is accomplished manually by use of the push buttons of switch 302.

While the "up" button of switch 302 is pressed (assuming that the "stop" button is not pushed), alternating voltage from power line 332 is applied through closed hoist switch 141, in a manner to be explained, to one side of coil 441 and also to one side of solenoid 426 of relay 305. This actuates the 4-way valve of the hydraulic system of hoist 50, and energizes motor 307. As a result, hoist 50 raises cargo pallet 47 to the desired height, at which point the "up" button is released.

Voltage from power line 332 is applied through line 422, contact 431 of relay 305, and line 432 to terminal 433 of push button switch 302. With the "stop" button not pressed, terminals 433 and 434 of switch 302 are connected. The latter terminal is connected to terminals 450 through 455 on one side of switch 302. While the "up" button is pressed, terminal 455 is connected with terminal 456 on the other side of the switch. Terminal 456 is connected through line 440 to one side of coil

441. The same alternating voltage from power line 332 is applied from terminal 456 through the other branch of lead 440 to terminals 439 and 430 of hoist switch 141. From there it is applied through line 429, terminal 428 of relay 319, and line 427 to solenoid 426 of relay 305.

For the majority of airplanes the forwardmost cargo hold 35 is located considerably higher than the other two holds 33 and 34. This is shown in Figure 1. For this reason, it is more difficult to raise hoist 50 accurately to the desired height upon the first try by the operator. If the "up" button is pressed too long, cargo hoist 50 will rise too far and it will be necessary to bring it back down to the desired position with respect to cargo hold 35. A "down" button of the type used in the circuit of cargo hoist 49 would not be suitable for this because of its connection with a timer, which assures that once started down the hoist will continue moving down and remain in its collapsed position for a predetermined interval of time. The "jog down" button is added to cargo hoist 50 to provide the necessary selective control which the operator needs for accurate positioning of the elevated hoist.

The circuit in which the "jog down" button is connected includes no timer, and the circuit is thus effective only while the "jog down" button is pressed by the operator. Thus, simply by pushing the button the desired length of time, the operator may control accurately how far down elevating members 131 and 132 of cargo hoist 50 are brought before they are stopped in position for loading or unloading of cargo pallet 47. If the operator—because of the difficulty of estimating the height of cargo pallet 47 from the ground when cargo hoist 50 is raised to substantially its full height—makes an error and brings the pallet back down too far, this can easily be corrected by his pushing the "up" button once again.

Voltage from power line 330 is applied to one side of coil 457 of solenoid 312 through line 420, terminal 442 of relay 305, and line 443. So long as the "jog down" button is pressed (and the "stop" button is not pressed), voltage from power line 332 is applied to the other side of coil 457 through line 422, terminal 431 of relay 305, line 432, terminals 433, 434, 450 through 453, and 458 of push button switch 302, lead 459, and terminal 460 of relay 319. This energizes solenoid 312 which actuates the 4-way valve in the hydraulic system of cargo hoist 50 to put it in condition to cause hydraulic pressure to be applied at the top of the hydraulic rams of hoist 50.

With the "jog down" button pressed (and the "stop" button not pressed), the voltage of power line 332 which is applied to terminal 452 of push button switch 302 is also applied, through terminals 461 and 462 of switch 302, leads 463 and 429, terminal 428 of relay 319, and lead 427, to one side of solenoid 426 of relay 305. This energizes motor 307.

When cargo pallet 47 has been unloaded by transferring its load of cargo into hold 35, it may be desirable to bring the cargo pallet down part way toward conveyor belt 40 to await the time when pallets 45 and 46 will have been started back toward the cargo accumulation station and thus the track will be clear for pallet 47 to leave plane 36 and return to the cargo accumulation station. Holding relay 319 and limit switch 318 are employed in the circuits by which this is accomplished.

Voltage from power line 330 is applied to one side of solenoid 520 of holding relay 319 through line 420, terminal 442 of relay 305, and lines 443 and 521. When the "down" button is pressed, voltage from power line 332, which is present at terminal 451 of push button switch 302, is communicated to terminal 522 of switch 302 and from there by lead 523 to the other side of solenoid 520 of holding relay 319.

As soon as the contacts of relay 319 are closed by this energizing of solenoid 520, holding contacts 524 and 525 provide a parallel connection through which the voltage of power line 332 is applied to lead 523 and

thus to solenoid 520. Holding contacts 524 and 525 are connected by lead 526 to normally closed terminals 527 and 528 of limit switch 318. Terminals 528 is connected through lead 435 with terminal 434 of push button switch 302. It is seen that so long as terminals 527 and 528 of limit switch 318 are closed and the "stop" button of switch 302 is not pressed, holding contacts 524 and 525 are in communication with power line 332.

With holding relay 319 energized, the operator may release the "down" button and cargo hoist 50 will nonetheless continue to move downward. Voltage from power line 332 is applied, as already explained above, to terminal 524 of holding relay 319. With the contacts of relay 319 closed, terminal 524 is connected with terminal 428 of that relay and thus to one side of solenoid 426 of relay 305. At the same time, terminal 524 of relay 319 is connected with terminal 460 of the same relay. The latter terminal is connected with coil 457 of solenoid 312. Energizing solenoid 426 and coil 457 starts motor 307 and simultaneously actuates the 4-way valve in the hydraulic system of cargo hoist 50 to cause the hoist to move down.

Limit switch 317 is positioned on cargo hoist 50 in a manner similar to limit switch 315 on hoist 49. Limit switch 318 is attached to cargo hoist 50 in somewhat the same manner, but is positioned so as to be actuated at a second predetermined height which is above the predetermined height at which limit switch 317 is actuated. When cargo hoist 50 has dropped to the point at which switch 318 is actuated, normally closed terminals 527 and 528 are disconnected and consequently voltage from power line 332 is no longer applied at terminal 524 of holding relay 319. Motor 307 and the 4-way hydraulic valve are thus no longer energized. Cargo hoist 50 stops its descent at this point.

As will be explained below, the separate circuits for cargo hoists 48, 49 and 50 are interlocked to prevent any hoist from lowering its associated cargo pallet, unless the next pallet between that hoist and the cargo accumulation station has already been lowered to within a predetermined distance of conveyor belt 40 to start its journey back toward the cargo accumulation station. As soon as this condition prevails at the outermost plane loading station where cargo hoist 50 has dropped pallet 47 to the predetermined height at which limit switch 318 was actuated, pressing the "down" button of switch 302 will cause hoist 50 to continue its downward movement and pallet 47 will come into frictional engagement with moving endless conveyor belt 40.

Voltage from power line 332 is applied (so long as the "stop" button is not pressed) to terminal 450 of push button switch 302. With the "down" button closed, this voltage is transmitted to the other side of switch 302 and from there by lead 539 to solenoid 540 of timer 541. The opposite side of solenoid 541 is connected by lead 542 to terminal 543 of limit switch 318. Normally open terminals 543 and 544 of switch 318 have been closed by actuation of limit switch 318. Normally closed terminals 545 and 546 of limit switch 317 have not yet been opened by the descent of cargo hoist 50, since switch 317, as explained above, is located below switch 318. Lead 547 connects terminal 546 with the interlock circuit of cargo hoist 49 and lead 548 provides a return. Lead 548 connects with lead 443, terminal 442 of relay 305, line 420, and power line 330. Thus the potential difference between power lines 332 and 330 is placed across solenoid 540 of timer 541.

As long as contacts 549 and 550 of timer 541 are held closed (and the "stop" button is not pushed) the voltage of power line 332 which is applied at terminals 433 and 434 of push button switch 302 is applied also through leads 435 and 551, terminals 550 and 549 of timer 541, and leads 555 and 523 to solenoid 520 of holding relay 319. This energizes motor 307 and coil 457 of solenoid 312 of the 4-way hydraulic valve for hoist 50,

as was the case when relay 319 was closed previously. Cargo hoist 50 therefore continues its descent and remains down, even though hoist switch 141 is kept closed by the presence of cargo pallet 47 until the pallet has been moved off the hoist.

Closing relay 319 does not bring holding contacts 524 and 525 into play at this juncture because terminals 527 and 528 of limit switch 318 have been opened earlier by the descent of hoist 50. Thus relay 319 continues actuated only so long as the contacts of timer 541 remain closed. When the timer opens, holding relay 319 is de-energized. The electrical system of cargo hoist 50 is then in condition to be actuated automatically by a subsequent arrival of cargo pallet 47 at the plane loading station of hoist 50, when the pallet has been loaded again at the cargo accumulation station and has returned from there with its new load.

The electrical circuit for operation of cargo hoist 48 corresponds to the circuit for hoist 49, which has already been described above in detail. Relay 303 for hoist 48 corresponds to relay 304 for hoist 49. Power from power lines 330, 331 and 332 is transmitted through relay 303, when solenoid 570 is energized to close the contacts of the relay, to be applied to three-phase electrical motor 306.

Solenoid 570 is energized by the closing of limit switch 316 (corresponding to limit switch 315 of cargo hoist 49) and hoist switch 313 (corresponding to switch 122 of cargo hoist 49). Voltage from power line 332 is applied through lead 571, terminals 572 and 573 of limit switch 316, terminals 574 and 575 of hoist switch 313 and lead 576 to one side of solenoid 570 of relay 303. The other side of solenoid 570 is connected to power line 330 in a manner similar to the connection of solenoid 338 of relay 304 for cargo hoist 49.

Voltage from power line 332 is also applied at terminal 577 of hoist switch 313 when closing of the switch connects terminals 574 and 577. Lead 578 transmits this voltage to terminals 579, 580 and 581 of push button switch 300. Lead 582 applies the voltage to one side of coil 583 of solenoid 311 of the 4-way valve for the hydraulic system of cargo hoist 48. The other side of coil 583 is connected through lead 584 with power line 330.

Energizing of motor 306 and coil 583 in the manner described causes hoist 48 to raise cargo pallet 45 automatically to the predetermined height at which normally open limit switch 316 is permitted to open. Further raising of pallet 45 is accomplished by the manual operation of the "up" button of switch 300, in the same manner as described for cargo hoist 49. Likewise, cargo hoist 48 is lowered in the same manner as was hoist 49 by operation of the "down" push button and the resulting energizing of solenoid 585 of timer 586.

55 Interlock between one cargo hoist and others

As already mentioned above, in a system employing the cargo elevator of this invention, such as the system shown in Figure 1, it is important that no cargo pallet start downward toward frictional engagement with conveyor belt 40 until the next cargo pallet between it and the cargo accumulation station has been lowered to within a short distance of conveyor belt 40, on which it will ride back toward the cargo accumulation station.

In the system shown, cargo pallet 45 is always the first to return to the cargo accumulation station. It is followed by pallets 46 and 47 in that order. If this were not arranged, a cargo pallet returning to the cargo accumulation station might collide with an intervening hoist which had not yet lowered its cargo pallet onto conveyor belt 40. Pallet 47, for example, might collide with cargo hoist 49, unless the hoist had already been lowered and had permitted cargo pallet 46 to roll off elevating members 51 and 52 onto tracks 41 to be propelled back to the cargo accumulation station.

70 The order in which cargo pallets 45, 46 and 47 return

from plane 36 to the cargo accumulation station is controlled by an interlock system which connects the electrical circuits of the three cargo hoists with which the pallets are associated. In the interlock system, the energizing circuit of the timer of each cargo hoist is connected through the limit switch which is employed on each preceding cargo hoist to stop at a predetermined height the automatic raising of that cargo hoist and its associated pallet.

There is no interlock circuit which bars lowering of cargo pallet 45 by cargo hoist 48, as there is always a clear track between the plane loading station at which hoist 48 is located and the cargo accumulation station. As is seen from Figure 27, one side of solenoid 585 of timer 586 is connected through lead 584 to power line 330. The other side of solenoid 585 is connected through lead 587 to terminal 588 of push button switch 300. Whenever the "down" button of switch 300 is pressed, terminals 588 and 589 of the switch are connected. Terminal 589 is connected with terminal 590 of the same switch, and when the "stop" button is not pressed terminals 590 and 591 are connected. Leads 592 and 571 connect terminal 591 with power line 332. Thus timer 585 is actuated whenever the "down" button is pushed, and cargo hoist 48 immediately proceeds to lower cargo pallet 45 until the pallet establishes frictional contact with conveyor belt 40 and starts back toward the cargo accumulation station.

Timer 393 of the electrical circuit of cargo hoist 49, however, cannot be actuated until cargo hoist 48 at the innermost plane loading station has been lowered to the predetermined height at which normally open limit switch 316 is closed. Until that time, pressing the "down" button of push button switch 301 cannot energize motor 200 or coil 408 of solenoid 310 of 4-way valve 208. As already explained above, voltage from power line 332 is applied to one side of solenoid 392 of timer 393 whenever the "down" button of switch 301 is pressed. The other side of solenoid 392 is connected with power line 330 through lead 394 and terminals 395 and 396 of limit switch 316, leads 397 and 372, terminal 334 of relay 304, and line 333. When terminals 395 and 396 are connected by the closing of limit switch 316, cargo hoist 49 can be moved downward. Before this happens, however, the hoist remains at its elevated position even if the "down" button is pressed.

The electrical circuit which includes the "jog down" button of push button switch 302 of cargo hoist 50 is not interlocked with the electrical circuits of the other hoists. Thus, pressing the "jog down" button will bring elevating members 131 and 132 of hoist 50 down to the predetermined height at which limit switch 318 is actuated. At this point the circuit of the "jog down" button is rendered ineffective.

The circuit of cargo hoist 50 which includes the "down" button of push button switch 302, like the corresponding circuit of hoist 49, is interlocked with the electrical circuit of the cargo hoist which is the next hoist along the path to the cargo accumulation station. When hoist 50 has been lowered to the point at which limit switch 318 has been actuated, terminals 543 and 544 of that switch are connected. As the hoist at this time is above the point where limit switch 317 will be actuated, terminals 545 and 546 of switch 317 are still closed. It is seen that one side of solenoid 540 of timer 541 is connected at this juncture, through lead 542, terminals 543 through 546, and lead 547, with terminal 552 of limit switch 315 of cargo hoist 57.

Until cargo hoist 49 has been lowered far enough to close limit switch 315, timer 541 of cargo hoist 50 cannot be actuated because of normally open terminals 552 and 553 of switch 315. However, as soon as cargo hoist 49 is lowered far enough to close switch 315, terminals 552 and 553 are connected and a circuit is completed from there through leads 548 and 443, terminal

442 of relay 305, and line 420 back to power line 330. As already explained above, pressing the "down" button of switch 302 places voltage from power line 332 on the other side of solenoid 540 of timer 541. Thus, when the "down" button is pressed after cargo hoist 49 has closed limit switch 315, timer 541 of hoist 50 is actuated, and motor 307 and coil 457 are energized to cause cargo hoist 50 to be lowered into its collapsed or down position.

The interlock circuit just described assures that in the system shown in Figure 1 cargo pallets 45, 46 and 47 always return from plane 36 to the cargo accumulation station in that exact order. It may be arranged that the pallets always stand at the cargo accumulation station in the order in which they arrive from the plane. Thus, when they leave to be moved on out to plane 36 again, the pallets always move in reverse order: pallet 47, 46, and then 45. This controlled order of cargo pallet movement takes advantage most effectively of the high degree of automatic operation which is displayed by the preferred embodiment of the cargo elevator of this invention.

The above detailed description of this invention has been given for clearness of understanding only. No unnecessary limitations should be understood therefrom, as modifications will be obvious to persons skilled in the art.

I claim:

1. Cargo handling apparatus comprising: a hoist adapted to raise and lower cargo, said hoist including an elevating member; switch means for selectively actuating said elevating member to be raised or lowered; a mobile cargo pallet, said pallet including means adapted to trip said hoist switch automatically when the pallet is in a position in which it may be lifted by the hoist; a limit switch blocking further automatic rise of the elevating member of the hoist after it reaches a first predetermined height; manual switch means for actuating the hoist to lift said cargo from said first predetermined height to a second predetermined height; and propelling means for moving the pallet to said hoist, said propelling means being adapted to be rendered inoperative when the cargo pallet is raised a predetermined height above the position it occupies upon its arrival at the hoist.

2. Cargo handling apparatus for use with an endless conveyor belt for transporting cargo from a cargo accumulation station to a hoisting station which comprises: a hoist adapted to raise and lower cargo, said hoist including an elevating member; switch means for selectively actuating the elevating member of the hoist to be raised or lowered; and a mobile cargo pallet, said pallet including means adapted to trip said hoist switch automatically when the pallet is in a position in which it may be lifted by the hoist, said pallet being provided on its bottom side with a traction member, said traction member being adapted to be pressed against said conveyor belt to produce a frictional engagement between the traction member and conveyor belt tending to propel the pallet toward the cargo hoist, said frictional engagement being broken when the pallet is lifted a predetermined height above the conveyor belt.

3. Cargo handling apparatus for use with an endless conveyor belt for transporting cargo from a cargo accumulation station upon supporting and guiding track means to a hoisting station which comprises: a hoist adapted to raise and lower cargo, said hoist including an elevating member; switch means for selectively actuating said elevating member to be raised or lowered; and a mobile cargo pallet, said pallet including wheels adapted to ride upon said supporting and guiding track and including wheels adapted to ride upon the elevating member of said hoist and there to trip said hoist switch automatically when the pallet is in a position in which it may be lifted by the hoist, said pallet being provided on its bottom side with a traction plate, said plate being adapted to be pressed against said conveyor belt to produce a

frictional engagement between the plate and conveyor belt tending to propel the pallet toward the cargo hoist, said frictional engagement being broken when the pallet is lifted a predetermined height above the conveyor belt

4. The cargo handling apparatus of claim 3 in which the pallet has wheel bearing front and rear axles, said axles being pivotally mounted on the pallet so as to rotate in the horizontal plane, whereby the pallet may follow curves in the conveyor belt and associated track.

5. The cargo handling apparatus of claim 4 in which the wheels that are adapted to ride on the inner side of the curved path are flanged; a spring-loaded traction plate is attached to each of said axles near the center of the axle; a connecting rod runs between the inner end of one axle and the outer end of the other axle; and the pallet carries tensioning means adapted to urge one of said axles continuously to return to its normal operative position at right angles to the longitudinal axis of the pallet.

6. A cargo elevator for use with an endless conveyor belt for transporting cargo from a cargo accumulation station along supporting and guiding track means to a hoisting station which comprises: a hoist adapted to raise and lower cargo, said hoist including two elevating platforms spaced from each other and adapted to rise and fall at the same rate when raising and lowering cargo, said elevating members being supported by upright members which sweep from a position making an acute angle with the horizontal up toward a vertical position as said hoist raises cargo; switch means for selectively actuating said elevating member to be raised or lowered; a mobile cargo pallet, said pallet including wheels adapted to ride upon said supporting and guiding track and wheels adapted to ride upon the elevating member of said hoist and there to trip said hoist switch automatically when the pallet is in a position in which it may be lifted by the hoist, said pallet being provided on its bottom side with a traction plate, said plate being adapted to be pressed against said conveyor belt to produce a frictional engagement between the plate and conveyor belt tending to propel the pallet toward the cargo hoist, said frictional engagement being broken when the pallet is lifted a predetermined height above the conveyor belt; a limit switch blocking further automatic rise of the elevating member of the hoist after it reaches a first predetermined height; and manual switch means for actuating the hoist to lift said cargo from said first predetermined height to a second predetermined height.

7. A cargo elevator for handling cargo moving to and from the elevator which comprises: two elevating platforms spaced from each other; a hydraulic ram associated with each of said elevating platforms adapted to raise and lower the platform upon application of hydraulic pressure to the ram, each of said rams having the same performance characteristics upon application of equal hydraulic pressure to the rams; a source of hydraulic pressure, said source applying pressure greater than a predetermined amount to said hydraulic ram at all times; flow control means in each of said two hydraulic systems comprising a ram and pressure source, said means regulating the hydraulic pressure applied to the ram to keep it from rising at any time above said predetermined maximum amount; switch means for selectively actuating said hydraulic ram to raise or lower its associated elevating platforms; a mobile cargo pallet, said pallet including means for tripping said switch automatically when the pallet is in a position in which it may be lifted by the elevating platforms; and propelling means for moving the pallet to the cargo elevator, said propelling means being rendered inoperative when the pallet is raised a predetermined height above the position it occupies upon its arrival at the cargo elevator.

8. A cargo elevator for use with an endless conveyor belt for transporting cargo from a cargo accumulation station upon supporting and guiding track means to a

hoisting station, a portion of the path of the conveyor belt being curved, which comprises: a hoist adapted to raise and lower cargo, said hoist including an elevating member; switch means for selectively actuating said elevating member to be raised or lowered; a mobile cargo pallet, said pallet having wheel bearing front and rear axles pivotally mounted on the pallet so as to rotate in the horizontal plane, the wheels carried by said axles being adapted to ride upon said supporting and guiding tracks, said pallet also including wheels adapted to ride upon the elevating member of said hoist and there to trip said hoist switch automatically when the pallet is in a position in which it may be elevated by the hoist; and a spring loaded traction plate rotatably attached to each of said axles, said plate being adapted to be pressed against said conveyor belt to produce a frictional engagement between the plate and the conveyor belt tending to propel the pallet toward the cargo hoist, said plate being further adapted to have said frictional engagement broken when the pallet is moved a predetermined height above the conveyor belt.

9. A cargo elevator for use with an endless conveyor belt for transporting cargo from a cargo accumulation station along supporting and guiding tracks to a hoisting station which comprises: a hoist adapted to raise and lower cargo, said hoist including an elevating member; switch means for actuating said elevating member to be raised; a mobile cargo pallet, said pallet including means adapted to operate said hoist switch automatically when the pallet is in a position in which it may be lifted by the hoist; traction means on the bottom side of said pallet, said means being adapted to be pressed against said conveyor belt to produce a frictional engagement between said means and belt sufficient to propel the pallet toward the cargo hoist, said frictional engagement being broken when the pallet is lifted a predetermined height above the conveyor belt; limiting means blocking further automatic rise of the elevating member of the hoist after it reaches a second predetermined height; means for manually actuating said elevating member to be raised above said second predetermined height; and means when actuated momentarily by the operator to automatically lower said elevating member to its bottom position and hold the elevating member in that position for a predetermined time after the cargo pallet has been moved by the conveyor belt from the position in which it operates the hoist switch.

10. A cargo elevator for use with an endless conveyor belt for transporting cargo from a cargo accumulation station along supporting and guiding tracks to a hoisting station which comprises: a hoist adapted to raise and lower cargo, said hoist including an elevating member; switch means for actuating said elevating member to be raised; a mobile cargo pallet, said pallet including means adapted to operate said hoist switch automatically when the pallet is in a position in which it may be lifted by the hoist; traction means on the bottom side of said pallet, said means being adapted to be pressed against said conveyor belt to produce a frictional engagement between said means and belt sufficient to propel the pallet toward the cargo hoist, said frictional engagement being broken when the pallet is lifted a predetermined height above the conveyor belt; limiting means blocking further automatic rise of the elevating member of the hoist after it reaches a second predetermined height; means for manually actuating said elevating member to be raised above said second predetermined height; means for manually actuating said elevating member to be lowered from its highest position to a third predetermined height above said second predetermined height; and means adapted when actuated momentarily by the operator to automatically lower said elevating member to its bottom position and hold the elevating member in that position for a predetermined time after the cargo pallet has been

moved by the conveyor belt from the position in which it operates the hoist switch.

11. A cargo elevator for use with an endless conveyor belt for transporting cargo from a cargo accumulation station along supporting and guiding tracks to a hoisting station which comprises: a hydraulic hoist adapted to raise and lower cargo, said hoist including an elevating member; switch means for actuating the hydraulic system of the hoist to raise said elevating member; a mobile cargo pallet, said pallet including means adapted to operate said hoist switch automatically when the pallet is in a position in which it may be lifted by the hoist; traction means on the bottom side of said pallet, said means being adapted to be pressed against said conveyor belt to produce a frictional engagement between said means and belt sufficient to propel the pallet toward the cargo hoist, said frictional engagement being broken when the pallet is lifted a predetermined height above the conveyor belt; a limit switch adapted to block further automatic rise of the elevating member of the hoist after it reaches a second predetermined height; a manual switch for actuating the hydraulic system of said hoist to raise said elevating member above said second predetermined height; a second manual switch adapted so long as it is closed to actuate the hydraulic system of the hoist to lower said elevating member from its highest position to a third predetermined height above the second predetermined height; a timer adapted when energized to actuate said hydraulic system to automatically lower said elevating member from said third predetermined height to its bottom position and hold the elevating member in that position for a predetermined time after the cargo pallet has been moved by the conveyor belt from the position in which it operates the hoist switch; and a third manual switch adapted when actuated momentarily by the operator to energize said timer.

12. A cargo loading and unloading device for aircraft and the like comprising a longitudinally extending end-

less belt conveyor, a hoist having spaced elevating members flanking the conveyor, and positioned substantially at or below the level of the conveyor when the hoist is in its lowermost position, a mobile cargo pallet adapted to be moved by said conveyor to and from the hoist, said elevating members being unconnected above the level of the conveyor whereby the hoist provides a clear unobstructed path for movement of said cargo pallet into operative position with respect to the hoist, and means for actuating said elevating members in unison when said cargo pallet is in such operative position, said pallet being provided on its bottom side with a traction member, said traction member being adapted to be pressed against said conveyor belt to produce a frictional engagement between the traction member and the conveyor belt tending to propel the pallet toward said cargo hoist, said frictional engagement being broken when the pallet is lifted a predetermined height above the conveyor belt.

13. A cargo loading and unloading device as set forth in claim 12 in which said actuating means includes a switch mounted on and movable with the hoist and is automatically actuated for lifting the hoist by movement of said cargo pallet into said operative position.

14. A cargo loading and unloading device as set forth in claim 12 in which said hoist is mounted on roller means for longitudinally shifting the position of said hoist relative to the conveyor.

15. A cargo loading and unloading device as set forth in claim 13 in which said hoist is mounted on roller means for longitudinally shifting the position of said hoist relative to the conveyor.
